FORGING PRESS

Harold N. Anderson, Rocky River, Ohio

Application May 28, 1943, Serial No. 488,806

10 Claims. (Cl. 78—39)

1

This invention relates to improvements in a press of the type used for forging and drawing metals and for similar operations. The improvement relates to the changing of the position of the moving die generally while the latter is in motion and provides a means for varying the position of the stroke of a reciprocating press while always providing a positive stroke between rigidly supported members.

An object of the present invention is the provision, in a machine having a die whose motion is controlled by a rotating shaft, of means for changing the position of the moving die relative to the cooperating die while the shaft is in rotation.

Another object of the present invention is the provision of novel means for automatically advancing a moving die toward a cooperating die while the moving die is in motion.

A more specific object of the present invention relates to that type of machine in which a die is moved by means of a rotating crank and consists in the changing of position of the crankshaft in a novel manner so as to vary the approach stroke of the dies.

My invention also provides a novel means for shifting the position of a shaft by means of eccentric bearings so as to vary the position of a die driven from that shaft.

Other improvements found in my present invention relate to a specific hydraulic means for carrying out the above named purposes.

Other advantages of my improved mechanism will be apparent from the accompanying drawings and specification and the essential features will be set forth in the appended claims.

In the drawings

Fig. 1 is a front elevational view of a forging press embodying my invention;

Fig. 2 is a side elevation of the same;

Fig. 3 is an enlarged fragmental sectional view taken along the line 3—3 of Fig. 1;

Fig. 4 is a diagrammatic view illustrating the hydraulic system for controlling the parts illustrated in Figs. 1 to 3;

Figs. 5 and 6 illustrate other positions of one of the valves shown in Fig. 4; while

Fig. 7 is a detail of a throttling valve shown in Fig. 4.

One of the disadvantages of forging presses, drawing presses and similar metal working machinery in common use today is that they must work at relatively low speeds if accurate die work is to be performed. Obviously this remark does not apply to high speed hammers, but this type

2

of equipment is not adapted for accurate die work. The present invention provides means whereby a moving die or hammer may be driven at relatively high speed toward a piece of metal to be formed and which is held in a rigidly fixed coacting die or platen. The stroke of the moving die is very accurately controlled so that an exact predetermined amount of work may be done on the metal at any one stroke and yet the machine makes use of the momentum of the moving die to perform work. My invention is applicable to machines of this type whether they be vertical, as illustrated in the accompanying drawings, or horizontal or inclined.

15 In the drawings I have illustrated my invention as applied to a forging press of the vertical type. This press comprises a frame 10 in the lower portion of which is rigidly fixed a platen or die 11. In the upper portion of the frame suitably guided 20 for sliding movement in a vertical direction is the slide or movable platen 12. Suitable dies may be provided in either or both of the platens for producing the desired work in a piece of metal by forging or drawing operations or the like, as 25 will be readily understood by those skilled in this art. The movement of the platen 12 is provided by means of a rotatable shaft 13 which has a crank throw 14 operatively connected by the link or connecting rod 15 which is pivotally mounted 30 in the platen 12 at the point 16. It will be understood that wherever I have referred to a "crank connection" between the rotatable shaft and the moving platen I intend to include such connections as the Scotch yoke and other similar equivalent connections. The means for rotating shaft 35 13 comprises a large gear 17 rigidly fixed on or clutched to shaft 13 and meshing with pinion 18 on jack shaft 19. At its opposite end this jack shaft carries a combined pulley and flywheel 20 40 which has a suitable driving belt connection 21 with the pulley 22 of motor 23.

Means is provided for varying the position of the upper end of connecting rod 15 relative to the frame 10 so as to vary the stroke of the platen 12, thus varying the relative approach of the movable platen to the stationary platen 11. In the embodiment shown here the shaft 13, as best seen in Fig. 3, is mounted in a bearing 24 which is eccentric with respect to the axis of shaft 13. 50 The bearing 24 is rigidly mounted in a shell 25, which in turn may be mounted in suitable bearings 26 in the frame 10. The construction is the same in both side portions of the frame 10 and the two shells 25, as clearly shown in Fig. 1, are 55 provided with arms 25a which converge centrally

and toward the rear of the machine to a common point 27 where they have a pivot connection with means for rotating the shells and therefore the eccentric bearings so as to vary the position of shaft 13 relative to the frame 10. As best seen in Fig. 3, I have indicated means for moving the arms 25a through substantially a 90° angle from the full line position to the dot-dash position there indicated, which moves the center of shaft 13 from the upper position marked 13a to the lower position marked 13a'.

Preferably power means is utilized for moving the eccentric bearing as just described. To this end I have mounted a double acting cylinder and piston motor 28 on a trunnion mounting at the point 29. The piston 30 of this motor is connected by piston rod 31 with the pivot pin at the point 27. A pressure fluid supply system for motor 28 is provided through conduit 32 which is intended to be a supply from a pump or the like. The supply passes through four-way valve 33, conduit 34, valve 35, conduit 36, valve 37 and conduit 38 to the upper end of the motor cylinder.

Obviously the working portion of the stroke of platen 12 occurs on downward movement of the later approaching platen 11, and the non-working portion of the stroke is its upper portion. This non-working portion occurs partly on the up-stroke and partly on the down-stroke. The working portion of the stroke occurs when the platen 12 strikes the work resting on platen 11. Means is provided for opening valve 37 automatically during the non-working portion of the stroke and for closing the valve during the working portion of the stroke. Such a means is here shown comprising an arm 37a for rotating valve 37, this arm having an open slot 37b in its free end which engages a pin 39 carried by the platen 12. On the up stroke of platen 12, as best seen in Fig. 4, the valve is carried to open position as shown in full lines. On the down stroke of platen 12 the valve is carried to closed position, as shown in dot-dash lines.

The valve 35 is to control the rate of flow through conduits 34 and 36 to valve 37 when it is open. Any suitable valve may be used for this purpose, but as here indicated I have shown a rotatable cock having a V-shaped port 35a extending through the center thereof so that when the apex of the port begins to open a very nice control of the amount of fluid flowing is provided.

The valve 33 is under control of the operator and to this end I have shown an arm 33a for rotating the valve connected by link 40 with treadle 41 which extends to the front of the machine where it is provided with a foot-piece 42. The valve 33 has three positions as shown in Figs. 4, 5 and 6. The position shown in Fig. 4 corresponds to the full line position of treadle 41 and supplies pressure fluid as already described to the upper end of motor 28. The second position of the valve shown in Fig. 5 is a neutral position which cuts off the supply of fluid in either direction. This second position corresponds to the broken line position of treadle 41 in Fig. 4 and a heavy spring 43 is provided at this point so as to warn the operator upon further depression of the foot piece 42. The third position of valve 33 is illustrated in Fig. 6. This cuts off the supply of fluid from conduit 32 to conduit 34 as previously described and provides a flow from conduit 32 through conduit 44 to the lower end of motor 28 for operating piston 30 in the opposite direction. This third position of valve 33 occurs when pressure is removed from the foot piece 42, whereupon spring

45 (Fig. 4) moves treadle 41 to the dot-dash line position, moving valve 33 to the position of Fig. 6 just described.

It will be noted that valve 33 and its connections with motor 28 have been arranged for use of an incompressible fluid, such as oil. The passages of the valve are therefore arranged so that in the position of Fig. 4, when flow occurs between conduits 32 and 34 on the intake side, fluid exhausting from motor 28 flows from conduit 44 to conduit 46, which is intended to indicate a flow back to a tank or reservoir for the pump supplying conduit 32. In like manner, when valve 33 is in the position of Fig. 6 fluid flow is directly from conduit 32 to conduit 44 on the intake side and the return flow is from conduit 34 to conduit 46 back to the tank.

It is believed that the operation of my improved device will now be apparent. With the parts in the full line position of Figs. 3 and 4, the shaft 13 is in its uppermost position and the platen 12 is in its most remote position with respect to platen 11. Control button 47 or some similar control means is now operated to start motor 23. An abutment type of air clutch (not shown) in the drive from motor 23 to shaft 13 is then engaged. This produces rotation of shaft 13, which, by the crank connection 14, causes repeated vertical strokes of platen 12. If an article to be worked upon is held between the coating platens a stroke of predetermined length will produce a predetermined amount of work on the article until some change in eccentric bearing 24 occurs. If the operator depresses the foot piece 42 to the full line position of Fig. 4, fluid is supplied through valves 33, 35 and 37 at each upward stroke of platen 12. Since this occurs when the load is removed from the moving platen it is not very difficult to rotate the eccentric bearing. At each upward movement of platen 12 a shot of pressure fluid is supplied above piston 30, causing intermittent downward movement of the same, which carries with it the arms 25a so as to gradually rotate the eccentric bearing 24 to the dot-dash position of Fig. 3. The amount of each of these successive movements or the amount of the shot of fluid supplied at each operation of valve 37 depends upon the setting of the control valve 35 as will readily appear. The operator may maintain the foot piece 42 in the fully depressed position indicated at full lines in Fig. 4 as long as he desires the platen 12 to be moved closer to the platen 11 on each stroke. If at any time he desires two or more strokes without further relative approach between the two platens he simply decreases the pressure on the foot piece 42 until spring 43 moves to its unstressed position indicated in Fig. 4, whereupon the treadle is in the broken line position there shown and the valve 33 is in the neutral position of Fig. 5. In this position of the parts no movement of piston 30 occurs. Upon completion of the work upon the article the operator removes his foot permitting treadle 41 to move to the dot-dash position of Fig. 4 and placing valve 33 in the position of Fig. 6. This supplies fluid beneath piston 30 and returns the arms 25a to their uppermost position and turns the eccentric bearing 24 to the position indicated in full lines in Figs. 3 and 4. The parts are then in the position for operating upon another article.

The valve 33 might be arranged to supply fluid directly from conduit 32 to conduit 36 in the neutral position shown in Fig. 5, but other ways of removing pressure from the pump are well known,

such as a spring-loaded by-pass direct from the pump discharge to the supply tank.

It will be noted from Fig. 2 that the relationship between gear 17 and pinion 18 is such as to permit the downward movement of gear 17 along with shaft 13 in the manner just described without seriously interfering with the suitable meshing of the teeth of the gear and pinion. Other means are available for accommodating this downward movement of shaft 13, but the same forms no part of the present invention.

It will be seen from the above description that I have provided rigid support for platen 12 at all times with means for varying the position of platen 12 relative to platen 11 while the machine is operating and shaft 13 is rotating. The change of the stroke of platen 12 is always definite and is under the control of the operator. He may produce a small or large increment of approach between the coacting platens at each stroke of the movable platen and he may stop such approach movement or cause retrograde movement between the platens at any time he desires.

My improved device herein disclosed has the advantages of a press and of a hammer also. It is like a press in that the stresses are self-contained and the amount of deformation of the metal worked upon is predetermined by the setting of the dies. In hammer operations there is no predetermined distance between the dies at each stroke, but instead the amount of deformation occurring at each stroke of the hammer is dependent upon the resistance of the work. It has the advantage of a hammer over a press in that it permits a gradual approach of the dies, shaping the work by repeated blows, which refines the metal and which permits the removal of scale between blows. My improved device is able to duplicate the higher momentum of the hammer, forcing the metal into the sharp corners of the dies, if there be such.

What I claim is:

1. In a press of the type comprising a pair of coacting platens at least one of which is movable relative to the other in a substantially linear stroke movement, a rotatable shaft, an operative connection between said movable platen and said shaft including a connection eccentric with said shaft, and means operable by movement of the press for varying the eccentricity of said connection relative to said shaft.

2. In a press of the type comprising a pair of coacting platens at least one of which is movable relative to the other in a substantially linear stroke movement, a rotatable shaft, an operative connection between said movable platen and said shaft including a connection eccentric with said shaft, power means for varying the eccentricity of said connection relative to said shaft, and control means for said power means having an operative connection with said movable platen.

3. In a press of the type comprising a pair of coacting platens at least one of which is movable relative to the other in a substantially linear stroke movement, a rotatable shaft, an operative connection between said movable platen and said shaft including a connection eccentric with said shaft, power means for varying the eccentricity of said connection relative to said shaft, and operator-operable control means for causing said power means to vary the eccentricity of said connection in a manner to produce closer relative approach movement of said coacting platens, said control means being provided with means auto-

5 matically acting upon release of said control means by said operator to produce retrograde movement of said movable platen relative to said coacting platen.

4. In a press of the type comprising a pair of coacting platens at least one of which is movable relative to the other in a stroke movement, a rotatable shaft, a drive connection between said movable platen and said shaft, a bearing for said shaft eccentric of the latter, cylinder and piston motor means having an operative connection with said bearing for rotating the latter, a pressure fluid supply for operating said motor in a direction to vary the eccentricity of said bearing in a manner to produce closer relative approach movement of said coacting platens, a valve in said pressure fluid supply, and means for opening said valve responsive to a portion of said stroke when said movable platen is out of engagement with the work.

5. In a press of the type comprising a pair of coacting platens at least one of which is movable relative to the other in a stroke movement wherein in the working portion of the stroke occurs upon relative approach of said platens and the non-working portion of the stroke occurs upon relative recession of said platens, a rotatable shaft, a drive connection between said movable platen and said shaft, a bearing for said shaft eccentric of the latter, cylinder and piston motor means having an operative connection with said bearing for rotating the latter, a pressure fluid supply for operating said motor in a direction to vary the position of said bearing in a manner to produce closer relative approach movement of said coacting platens, a valve in said pressure fluid supply, means for opening said valve during the non-working portion of the stroke of said movable platen, and a second valve operator-controlled in series with said first named valve.

6. In a press of the type comprising a pair of coacting platens at least one of which is movable relative to the other in a stroke movement wherein in the working portion of the stroke occurs upon relative approach of said platens and the non-working portion of the stroke occurs upon relative recession of said platens, a rotatable shaft, a drive connection between said movable platen and said shaft, a bearing for said shaft eccentric of the latter, double-acting cylinder and piston motor means having an operative connection with said bearing for rotating the latter, a pressure fluid supply for operating said motor in a direction to vary the position of said bearing in a manner to produce closer relative approach movement of said coacting platens, a valve in said pressure fluid supply, means for opening said valve during the non-working portion of the stroke of said movable platen, and a second valve operator-controlled in series with said first named valve, said second valve having three positions, namely, a fluid supply position, a fluid cut-off position, and a third position adapted to supply pressure fluid for operating said motor in the opposite direction for producing rotation of said eccentric bearing in a manner to provide retrograde movement of said movable platen relative to said coacting platen.

7. In a press of the type described, a frame, a relatively fixed platen, a crankshaft, a movable platen carried thereby in position to coact with said fixed platen, said frame having spaced rigid members, axially aligned bearings equally eccentric with respect to said shaft and supporting the lat-

ter in said frame members, and means for simultaneously rotating said bearings to vary the distance between said platens.

8. In a press of the type comprising a pair of coacting platens at least one of which is movable relative to the other in a stroke movement, a rotatable shaft, an operative connection between said movable platen and said shaft, power means for varying the relative approach movement of said coacting platens, a power source for said power means, a control member for said source, means for moving said control member to power supply position responsive to a portion of said stroke when said movable platen is out of engagement with the work, and a second operator-operable control member connected with said power source in series with said first named control member.

9. In a press of the type comprising a pair of coacting platens at least one of which is movable relative to the other in a stroke movement, a rotatable shaft, an operative connection between said movable platen and said shaft, power means for varying the relative approach movement of said coacting platens, a power source for said power means, a control member for said source, means for moving said control member to power supply position responsive to a portion of said

stroke when said movable platen is out of engagement with the work, and a second control member connected with said power source in series with said first named control member and adjustable to vary the amount of power supplied upon movement of said first named control member to power supply position.

10. In a press of the type comprising a pair of coacting platens at least one of which is movable relative to the other in a stroke movement, a rotatable shaft, an operative connection between said movable platen and said shaft, power means for varying the relative approach movement of said coacting platens, a power source for said power means, a control member for said source, means for moving said control member to power supply position responsive to a portion of said stroke when said movable platen is out of engagement with the work, and a second operator-operable control member connected with said power source in series with said first named control member, said second control member having three positions, namely, a power supply position, a power cut-off position, and a third position for connecting said source to said power means to operate the latter in a manner to produce retrograde movement of said movable platen relative to said coacting platen.

HAROLD N. ANDERSON.
